OF BERLIN, GERMANY.

APPARATUS FOR DRYING AIR FOR METALLURGICAL PURPOSES.

No. 839,362.

Specification of Letters Patent.

Patented Dec. 25, 1906.

Application filed January 9, 1905. Serial No. 240,373.

To all whom it may concern:

Be it known that we, GIUSEPPE CATTANEO, mechanical engineer, a subject of the King of Italy, and a resident of Friedbergstrasse 32, Charlottenburg, near Berlin, Germany, and JULIUS SCHLESINGER, mechanical engineer, a citizen of the United States of America, and a resident of Geisbergstrasse 31, Berlin, Germany, have invented certain new and useful Improvements in Apparatus for Drying Blast - Air for Metallurgical Purposes, of which the following is a specification.

The present invention relates to apparatus for drying blast-air for metallurgical purposes.

In the drying of blast-air for metallurgical purposes by means of cooling apparatus have hitherto been used in which the air is cooled down by coming into contact with cold metallic surfaces—for instance, the surfaces of pipes through which cold brine is flowing, in which case the water separated from the air is deposited in the form of hoar-frost or rime on the surface of the pipes. When the layer of rime has become of a certain thickness, the cooling apparatus must be disconnected and put in working order again by thawing the layer of rime. Consequently two apparatuses at least are necessary, which serve alternately for cooling. Apart from the costs and complication of such a plant connected with transposing or change-over devices the plant in addition possesses the important defect that the layer of rime becoming deposited on the pipes not only impairs the transmission of cold, but also the resistance in the movement of the air, which is considerable from the outset and which is offered by the systems of pipes to the air as it sweeps through is increased in the course of the running of the plant, in consequence of the increasing narrowing of the cross-sectional area of the free space between the pipes. For this reason in the case of such cooling apparatuses an auxiliary blowing device or fan is employed, which relieves the blowing-engine from the work of suction.

The employment of several coolers to be used alternately, as well as the use of auxiliary blowing devices, is avoided by the method forming part of the subject-matter of the present application, which method renders it possible to work perfectly continuously.

The new apparatus brings the air into direct contact with a cooled liquid in the form of rain, so that there is substantially no obstruction to the flow of the air. The cooling preferably takes place down to below 0°; but according to the degree to which it is desired to dry the air the liquid may have a temperature above 0°. It has been proved to be particularly useful and practical for the liquid to have a temperature of from —3° to —5°. It is understood that the lower the temperature the greater the extraction of moisture will be. It is preferable to employ a liquid having hygroscopic qualities—such as, for instance, a solution of chlorid of magnesium, chlorid of calcium, chlorid of sodium, or the like.

The air is preferably passed through a chamber in which it is exposed to a shower of cold lye in the form of rain. By this means it comes into intimate contact with the colder lye, and the moisture which it contains in consequence of the sudden drop in temperature is deposited on the surfaces of the falling particles of liquid, as well as absorbed in consequence of the hygroscopic quality of the brine, so that the drying action is more intense than in the case where the cooling is effected indirectly by the walls of pipes. Of course the freezing of the cooling liquid at low temperature is prevented by a suitable content of the salts. Moreover, whereas the resistance offered to the air on its passage through a cooler provided with cooling-pipes increases more and more in consequence of the continually-growing layer of rime the resistance when using a shower of liquid as a means for cooling remains always equally low. Finally, cooling by means of a shower of liquid permits the work to be continuous without the use of transposing or change-over devices, as the moisture in the air is continually taken up by the brine, so that it is necessary merely to concentrate the lye again, which can be readily effected without interrupting the running of the plant. For this purpose it is only necessary to draw off and concentrate by evaporation a portion of the lye returning to the refrigerator. This drawing off and concentration can be effected either intermittently or continuously. A continuous concentration of the lye can also be effected either by passing through a concentrator, the whole liquid returning from

the air cooling and drying apparatus to the refrigerator, or by passing a part of this liquid through the concentrator. In the latter case the part of the liquid passing through the concentrator must be more strongly concentrated in order that when mixed with the part not concentrated by evaporation a solution of normal concentration may be obtained.

10 The plant represented in the drawing may serve for carrying out the method.

R is the air cooling and drying apparatus, in the top part of which distributing-pipes *a* are arranged, to which a suitable, preferably hygroscopic, liquid is supplied from a reservoir *c* in order to flow out through uniformly-distributed openings in the form of rain. Below each pipe *a* a number of shallow dishes or trays *b*, of sheet metal or the like, are arranged in the form of cascades. The brine passing from the pipes *a* on to the uppermost trays *b* drips or trickles from tray to tray and collects in the lower part of the chamber, from which it is conducted by a pipe *d* to the refrigerator K.

G is the blowing-engine, which sucks the air through the cooling and drying chamber R in the direction of the arrow and forces it to a blast-furnace H or to a Bessemer converter B or any other metallurgical furnace.

K is the refrigerator consisting of a tank *e*, for the cooling liquid and of a coil *f*, arranged in said tank and surrounded by the cooling liquid. Through the coil *f* the cooling medium circulates, which may be either ammonia, carbonic-acid sulfurous dioxide, or the like, creating cold by evaporation, as commonly known with refrigerating plants. A pipe *g* and pump *h* conduct the cooled liquid from the refrigerator K to the reservoir *c*. By means of a partition-wall *i* a compartment *k* is formed, said compartment being connected, by means of a pipe *l* and pump *m*, with the concentrator C. From the latter a further pipe *n* leads back to the part of the refrigerator containing the coil *f*. The concentrator consists of a boiler which is heated in any desired manner—for instance, by means of a coil *p*, supplied with steam. Between the refrigerator K and the concentrator C a heat-equalizer E is inserted, in which the cold liquid coming from the refrigerator K flows in the opposite direction to and is preliminarily heated by the warm liquid coming from the concentrator E; the warm current being at the same time cooled.

The liquid stands in the refrigerator K at the height of the upper edge of the partition-wall *i*. In consequence of the taking up of

the moisture by the liquid in the cooling and drying chamber R more liquid returns to the refrigerator K than is drawn from it, so that liquid continually flows over the wall *i* to the compartment *k*. When a definite quantity of liquid has collected here, it is pumped, by means of the pump *m*, through the pipe *l* and the heat-equalizer E to the concentrator C, so as to come in a concentrated condition through the pipe *n* and the heat-equalizer E to the refrigerator K.

The pump *m*, as specified, may be allowed to work intermittently in order always to let a certain quantity of liquid collect in the compartment *k*. It may, however, be kept running continuously if its output is so adjusted that it corresponds with the amount of moisture taken up in the cooling and drying chamber R.

What we claim as our invention, and desire to secure by Letters Patent, is—

1. Apparatus for drying blast-air for metallurgical purposes by passing a current of air through a shower of a cooled hygroscopic liquid, comprising the combination of a chamber, a plurality of groups of shallow trickling-trays arranged in the form of cascades within said chamber, and means for supplying the liquid to the uppermost tray of each group, substantially as described.

2. Apparatus for drying blast-air for metallurgical purposes by passing a current of air through a shower of a cooled hygroscopic liquid comprising the combination of a chamber, a plurality of groups of shallow trickling-trays arranged in the form of cascades within said chamber, and a supply-pipe, having uniformly-distributed openings, over each group of trays, substantially as described.

3. In combination, an air cooling and drying chamber, a refrigerator, a concentrator, a compartment, into which flows a quantity of liquid corresponding to the amount of moisture absorbed in the cooling and drying chamber, a pump for feeding this liquid to the concentrator, and a heat-equalizer in which the cold liquid coming from the refrigerator, and the warm liquid coming from the concentrator exchange their heat, substantially as described.

In witness whereof we have hereunto signed our names in the presence of two subscribing witnesses.

GIUSEPPE CATTANEO.
JULIUS SCHLESINGER.
